TIMING DEVICE FOR ELECTRIC CURRENT

Landon Ralls Calvert, Bloomfield, N. J., assignor
 to Westinghouse Electric & Manufacturing
 Company, East Pittsburgh, Pa., a corporation
 of Pennsylvania

Application May 25, 1940, Serial No. 337,157

18 Claims. (Cl. 219—4)

This invention relates to a timing device for electric current and, more particularly, to one for accurately regulating the time electric current is on within close and dependable limits.

The principal object of my invention, generally considered, is to provide apparatus for regulating the time an electric circuit is maintained, as for electric welding and other processes requiring predetermined amounts of energy.

Another object of my invention is the provision of a timing device for electric current, comprising adjustable discs or cams with high and low dwells, operated intermittently through a clutch and continuously running motor, whereby a circuit is closed when a "make" contact element drops from the high dwell on one contact disc, and opened when a "break" contact drops from the high dwell on another cam, the control of said discs being such that the circuit cannot again be accidentally closed.

A further object of my invention is the provision of a timing device for electric current, including a latch operated by a treadle, or other device conveniently put in motion by an operator, and connecting hook, which allows a stop bar and connected discs to rotate one revolution, or until said stop bar re-engages the latch after release by the hook.

A still further object of my invention is the provision of a timing device for an electric current, in which cam discs are employed which may be adjusted with respect to one another, and another disc or discs added to perform additional operations.

Special features of my invention are the employment of adjustable cam discs which rotate when released, or when the clutch which causes rotation of the carrying shaft is allowed to engage, each disc being formed with high and low dwells and resiliently-pressed contact elements engaging the same, one of said elements making a contact when it drops from the high to the low dwell of its disc, and the other breaking a contact when it drops from the high to the low dwell on its disc, and a conductor putting said elements in series with a load, in order to accurately predetermine the length of time an electric current is supplied to said load, by the angular displacement between the corresponding dwells on said discs, and means for varying said displacement to vary the length of time.

Other objects and features of the invention, relating to the particular arrangement and construction of the various parts, will become apparent as the description proceeds.

Referring to the drawings illustrating my invention:

Figure 1 is a side elevational view of welding apparatus embodying my invention.

Figure 2 is a front elevational view of the apparatus of Figure 1, with parts in vertical section.

Figure 3 is a vertical sectional view on the line III—III of Figure 2, in the direction of the arrows.

Figure 4 is a vertical sectional view on the line IV—IV of Figure 2, in the direction of the arrows, showing the timing discs in normal or inactive positions.

15 Figure 5 is a view corresponding to Figure 4, but showing the positions and the parts after the timing discs have moved until the "make" contact element has rotated clockwise and the cam engaged roller thereof dropped from the high 20 to the low dwell on its disc, to complete the circuit.

Figure 6 is a view similar to Figure 4, but showing a position subsequent to that of Figure 5 in which the "break" contact element has rotated clockwise and the cam engaged roller thereof dropped from the high to the low dwell on its disc, to break the circuit.

Figure 7 is a fragmentary top plan on the line VII—VII of Figure 2.

30 Figure 8 is a wiring or circuit diagram of the apparatus shown in Figures 1 to 7, inclusive.

Figure 9 is mainly in side elevation, like Figure 1, and on the line IX—IX of Figure 10, showing another embodiment of my invention.

35 Figure 10 is a front elevational view of the apparatus illustrated in Figure 9.

Referring to the drawings in detail, and first considering the embodiment of my invention illustrated in Figures 1 to 8, inclusive, there is shown a table or bench 11 on which is mounted a bracket 12, adjustably supporting the lower electrode 13 of apparatus for welding small parts, such as those forming incandescent electric lamps, radio tubes or the like.

40 The table 11 also carries a bracket 14 in which is journaled a shaft 15 serving to pivotally mount an arm 16 fixed on said shaft and carrying the upper electrode 17 for cooperating with the electrode 13 in performing the desired welding operations.

45 The electrode 17 is normally held in upper position away from the electrode 13, as by means of a spring 18 acting on a rearwardly projecting 50 arm 19 of a bell crank 20 pivoted on the shaft

55 arm 19 of a bell crank 20 pivoted on the shaft

15, and with its lower end connected to the bracket 14.

The other arm 21 of the bell crank 20, carries a flange 22 having an outer surface 23 cylindrically curved about the axis of the shaft 15. The surface 23 is normally engaged by a lug or roller 24 on an arm or crank 25, mounted on a shaft 26, journalled in the bracket 14, and carrying a make-and-break device 27, including, for example, a mercury contact tube 28 for intermittently closing and opening a circuit through conductors 29 and 31.

The shaft 26 is normally biased by the spring 32, acting between an arm 33 projecting therefrom and the bracket 14, so that the lug or roller 24 resiliently engages the cylindrical surface 23. The arm 21 also carries a cam device 34, pivotally mounted on a shaft 35 which projects therethrough, the other end of said shaft carrying an arm 36 from which a spring 37 extends to a stud 38 for resiliently urging the cam device 34 into engagement with the curved surface 23.

A tension spring 39 connects the bell crank arm 19 with an arm 41 fixed on the shaft 15, for resiliently urging the bell crank arm 21 against a stud or lug 42 on an arm 43 fixed on the shaft 15. Thus the electrode 17 is resiliently urged to its uppermost position by the spring 18 acting on the arm 19, and the arm 21 acting on the lug 42 of the arm 43 to urge the shaft 15 and arm 16 carried thereby in a counterclockwise direction, as viewed in Figure 1.

A treadle 44, pivoted to a floor bracket 45, as indicated at 46, is provided, and connected to the arm 21 by a chain or the like 47, passing over pulley 48 pivotally mounted at 49. When the operator 50 depresses said treadle, through the angle designated by the reference character 51, the electrode 17 is brought into engagement with that designated 13.

Upon further movement, or when the treadle has traversed the angle 52, the lug or roller 24 is caused to ride up on the cam device 34, and momentarily energize a solenoid 53 mounted in box 54, by turning the make-and-break device 27 sufficiently, by a corresponding movement of its shaft 26, that the mercury contact tube 28 is tilted, closing the solenoid circuit through the conductors 29 and 31.

Upon still further movement, the lug 24 drops off the hub of the device 34, opening the solenoid circuit. When the treadle has traversed the angle 55, the circuit is still open.

All this movement is accomplished by the crank arm 19 resiliently operating the arm 41 through the spring 39, to move the arm 16 and electrode 17, by means of the shaft 15 to which the parts are fixed. When the electrode 17 engages the cooperating electrode 13, further movement of the arm 21 merely places the spring 39 under greater tension, and causes said arm to depart from engagement with the lug 42. Upon release of the treadle 44, the parts return to initial positions, the lug 24 moving back between the curved surface 23 and the cam device 34 against the action of the spring 37, without again closing the solenoid circuit.

Beneath the table or bench 11 is mounted apparatus for impressing the desired amount of energy on the electrodes 13 and 17, or controlling the length of time during which the impressed power operates, which apparatus will now be described.

The reference character 55 designates a motor, or other prime mover operable at substantially

uniform speed, connected through reduction gearing 56 to shaft 57 on which is keyed a clutch element 58 formed with a series of holes or pockets 59. Aligned with the shaft 57, and journalled in suitable brackets 61 and 62, is a shaft 63, on which is keyed a clutch element 64 carrying arms 65 and 66. In the arms 65 and 66 is reciprocably mounted a clutch device 67, with a slightly pointed end portion 68 adapted to fit in any one of the pockets 59 of the clutch 58. The device 67 has a collar 69 between which and the arm 68 acts a compression spring 71 for urging the member 67 into one of the pockets 59 for clutching engagement with the member 58.

15 The parts are normally out of clutching engagement, however, by virtue of cam lever 72 pivoted to a bracket 73, as indicated by the reference character 74, and normally biased by tension spring 75, so that the end portion 76, comprising a lower beveled or camming portion 77, fits between the arm 65 and the collar 69, as shown most clearly in Figures 1, 2 and 7, and holds the clutch device 67 out of engagement with the member 58. It is only when the relay 53 is energized to raise the cam lever 72 through connecting rod 80, that the clutch device 67 is allowed to reciprocate to the left and engage the clutch member 68.

Such engagement causes the shaft 63 to be operated, from the continuously rotating member 58, for one complete revolution or until the collar 69 rides on the beveled or camming portion 77 of the cam lever 72. The lever 72 is merely raised instantaneously and then dropped, thereby withdrawing the pointed end portion 68 from engagement with the pocketed clutch member 58, and allowing the shaft 63 to stop.

30 The shaft 63 carries a plurality of cam discs 78 and 79, which are adjustably related with respect to one another, as by having one of the discs, as 79, fixed on the shaft 63, while having the other, (or others) as 78, rotatable thereon, but held in adjusted position by connection to an adjusting plate 81, keyed to the shaft 63 and 35 having an arcuate slot 82 receiving a stud or bolt 83 from the disc 78, adapted to be tightened for holding the disc 78 to the plate 81 in adjusted position.

40 The cam disc 78 is formed with a high dwell portion 84 and a low dwell portion 85, while the cam disc 79 is formed with a high dwell portion 86 and a low dwell portion 87. Cooperating with the cam disc 78 is a "break" contact device 88, pivoted at 89, and carrying a contact lug or roller 91, adapted to traverse the periphery of said disc when rotating, and moving from the high dwell surface 84 to the low dwell surface 85, during which movement the adjustable contact member 92 is withdrawn from engagement with the spring contact member 93 to break an electrical circuit therethrough.

45 The cam disc 79 is engaged by "make" contact device 94, pivoted at 95, and carrying a contact lug or roller 96, which rides back and forth between and on the dwells 86 and 87 thereof. When dropping from the high dwell 86 to the low dwell 87, the contact device 94 causes the adjustable contact member 97 to engage the resilient contact member 98 and close a circuit through the conductor 99, in series with the contacts 92 and 93, as shown most clearly in Figures 5 and 8.

50 The elements 98, 97, 99, 92 and 93 are in the circuit which connects the primary winding 101 of transformer 102 to the operating lines 103 and

104 through main switch 105. Therefore, when the clutch members 68 and 58 are engaged and the discs 79 and 78 rotated, starting from the position illustrated in Figures 4 and 8, the contact device 84 first drops from the high dwell 86 to the low dwell 87 to cause the contacts 97 and 98 to engage, energizing the transformer 102 and causing the secondary winding 103' thereof to supply the desired electrical energy to the electrodes 13 and 17, which at that moment are closed, through the electrical connecting element 60.

Power is supplied until the shaft 63 has rotated enough to allow the break contact device 88 to drop from the high dwell 84 to the low dwell 85, withdrawing the contact 92 from the contact 93, opening the circuit through the primary winding 101 of the transformer 102, and shutting off the power to the electrodes 13 and 17.

It will therefore be seen that a cycle of operations when using the apparatus of Figures 1 to 8, inclusive, is that the switches 105 and 106 are first closed to start the motor 55 and cause it to run continuously. The treadle 44 is then depressed by the operator through the angle 51, bringing the electrodes 13 and 17 into engagement with what is to be welded thereby, between the adjacent end portions. Further movement of the treadle, or until the angles 52 and 53 have been traversed, results in momentary energization of the solenoid 83, by the lug 24 riding up on the cam device 84, closing the mercury switch 28 momentarily, and then dropping back over the hub and on release of the treadle, returning under said cam device. The closing of the switch 28 causes the necessary energization of the solenoid 83, and the raising of the cam lever 72, to allow the clutch elements 57 and 58 to become engaged and cause the cam discs 79 and 78 to be turned only one complete revolution.

During this complete revolution, the electrodes 17 and 18 are energized for a length of time depending on the speed of rotation of the shaft 63 and the angular displacement between where the contact lever 90 drops off the high dwell 86 and where the contact lever 88 drops off the high dwell 84.

It will, therefore, be seen that with my apparatus, I am able to accurately determine the length of time electric current is delivered to electrodes 13 and 17, and thereby assure that the welding operation will be uniform, as well as that the application of energy during one operation of the treadle 44 will not be accidentally repeated.

Referring now to the embodiment of my invention illustrated in Figures 9 and 10, there is shown a bench or table 111 on which is mounted a bracket 112 adjustably supporting the lower electrode 13' of apparatus for welding small parts, as in the preceding embodiment.

The table 111 also carries a bracket 114 in which is journalled a shaft 15' serving to pivotally mount an arm 16', fixed on said shaft, and carrying an upper electrode 17', which is adapted to cooperate with the electrode 13' in the performance of welding operations.

The electrode 17' is normally held in its upper position, as illustrated, as by means of a spring 18' acting on the rearwardly projecting arm 19' of a bell crank 20', pivoted with respect to the shaft 15', and with its lower end connected to the bracket 114.

A tension spring 39' connects the bell crank arm 19' with an arm 41', fixed on the shaft 15',

and resiliently urges the bell crank arm 21' against a stud or lug 42' on an arm 43' fixed on the shaft 15'. Thus the electrode 17' is resiliently urged to uppermost position by the spring 18' acting on the arm 19' and the arm 21' acting on the lug 42' of the arm 43', to urge the shaft 15' and arm 16' carried thereby, in a counter-clockwise direction, as viewed in Figure 9.

A treadle 44' is pivoted to a floor bracket 45', as indicated at 46', and connected to the arm 21' by a chain or the like 47' passing over pulley 48' pivotally mounted at 49'. When the operator 50' depresses the treadle 44' to the position indicated by dotted lines 44'', the electrode 17' is brought into engagement with that designated 18'. Upon further movement, or when the treadle has moved to the position designated by the reference character 44'', the mechanism beneath the table for supplying the requisite amount of electrical energy to said electrodes is made operative for impressing the desired amount of energy on the electrodes 13' and 17', or for controlling the length of time which the impressed power operates, which apparatus will now be described.

The reference character 55' designates a motor or other prime mover connected through reduction gearing 56' to shaft 57' journalled in bracket 58'. The end of the shaft 57', remote from the reduction gearing 56', carries the normally moving driving element 108 of a friction clutch 109. Aligned with the shaft 57', and journalled in suitable brackets 61' and 62', is a shaft 63' on which is fixed a cooperating friction clutch element 111 resiliently pressed into operative engagement with the element 108, by compression coil spring 112, operating between it and the bracket 61'.

The shaft 63' carries a plurality of cam discs 78' and 79', which are adjustably related with respect to one another as by having one of the discs, as 78', fixed on the shaft 63', while having the other (or others), as 79', rotatable thereon but held in adjusted position by connection to an adjusting plate 81', keyed to the shaft 63', and having an arcuate slot 82' receiving a stud or bolt 83' from the disc 78', adapted to be tightened for holding the disc 78' to the plate 81' in adjusted position.

The cam disc 78' is formed with a high dwell portion 84' and a low dwell portion 85', while the cam disc 79' is formed with a high dwell portion 86' and a low dwell portion 87'. Cooperating with the cam disc 78' is a "break" contact device 88' pivoted and carrying a contact lug or roller 91', and associated with contacts for making and breaking a circuit, such as shown in Figure 8 for the device 88.

The cam disc 79' is engaged by a "make" contact device 94', pivoted, and carrying a contact lug or roller 95', which rides back and forth between the dwells 86' and 87' thereof, dropping from the high dwell 86' to the low dwell 87', making and breaking a circuit exactly like the contact device 88 in Figure 8.

In the present embodiment the shaft 63' carries a stop bar 113, fixed thereto, in adjusted position as by means of the set screw 114. The outer end portion of the stop bar 113 is normally engaged and held stationary by the arm 115 of a latch 116, normally urged in a counter-clockwise direction by spring 117, secured to its arm 118, and with its other end connected to an arm 119 secured to a bracket 121.

Rotation of the latch 116 in a counter-clockwise direction beyond its normal position, illustrated in full lines in Figure 9, is prevented by a suitable stop on bracket 121. The arm 118 of said latch 116 is engaged by a hooked end 122 of a connecting rod 123, pivoted to and extending from the treadle 44^a. Said rod is resiliently held in place against the latch arm 118, as by means of a tension spring 124 acting between it and a depending bracket 125. It will, therefore be seen that a depression of the treadle, beyond the point indicated in dotted lines, by the reference character 44^b, as to the position 44^a, first releases the stop bar, as by moving the arm 118 from engagement therewith, and allows the shaft 63^a to make one complete revolution, whereupon it is stopped by the latch 116, which goes back to normal position under the action of the spring 117 upon the hooked end 122 of the connecting rod 123 passing therebelow. Release of the treadle 44^a and its return to initial or full line position, as shown in Fig. 9, does not again release the stop bar 113, but merely allows the hooked end 122 of the connecting rod 123 to re-engage the arm 118, as illustrated.

This release of the stop bar 113 and rotation of the shaft 63^a, has the same effect in energizing the electrodes 17^a and 13^a which have been in contact, as the engagement of the clutch elements 57 and 58 in the preceding embodiment, and thereby effects a welding operating in a similar manner.

Thus a cycle of operations, when using the apparatus of Figures 9 and 10, is that after closing switches corresponding with those designated 105 and 106 in Figure 8, to start the motor 55^a and cause it to run continuously, the treadle 44^a is first depressed by the operator 50^a to the position 44^b, bringing the electrodes 13^a and 17^a into engagement with one another, or clamp articles to be welded therebetween.

A further movement of the treadle as to the position 44^c, results in release of the stop bar 113, allowing the cam discs 78^a and 79^a to be turned one complete revolution, during which the electrodes 17^a and 13^a are energized, as in the preceding embodiment, through a circuit including the electrical connecting element 60^a, for a length of time depending on the speed of rotation of the shaft 63^a and the angular displacement between where the contact lever 94^a drops off the high dwell 86^a and where the contact lever 88^a drops off the high dwell 84^a.

It will thus be seen that by use of the present embodiment, I am also able to accurately determine the length of time electric current is delivered to electrodes 13^a and 17^a, and thereby assure that welding or other operations will be uniform, as well as that the application of energy during one operation of the treadle 44^a will not be accidentally repeated, as control of the clutch through the treadle is terminated, either by the dropping of the lug 24 back over the hub of the cam device 84, (Fig. 3), or by the disengagement between the hooked end 122 of the connecting rod 123 and the arm 118 of the latch 116 (Fig. 9), until after return of said treadle to initial position.

Although preferred embodiments of my invention have been illustrated, it will be understood that I do not wish to be limited to the number of cam discs shown, or the use of the apparatus for welding operations, as another or other discs may be provided in order to perform preliminary heating or like operations or other processes. It

will also be understood that although I have shown the illustrated embodiments operated by means of a treadle, manual operation may be substituted, if desired.

5 I claim:

1. A timing device comprising a shaft, a plurality of cam means on said shaft, associated contact devices for timing the application of electrical energy during welding operations, 10 means for readily adjusting the relationship between one of said contact devices and its cam means to alter the amount of energy delivered, a continuously running motor, a clutch between said motor and shaft, a pivoted member controlling the operation of said clutch, a device movable by an operator to trip said member and make the clutch effective to turn the shaft and elements carried thereby through only a definite angle, and means terminating the control of 20 said pivoted member through said device, when the clutch is once made effective by normal movement, until after return of said device to initial position.

2. A timing device comprising a shaft, a plurality of cam means adjustably mounted on said shaft, a "make" contact device resiliently urged into engagement with one of said means, a "break" contact device resiliently urged into engagement with another of said means, a source 25 of electrical energy in series with said cam means and contact devices, means for readily adjusting the relationship between one of said contact devices and its cam means to alter the amount of energy delivered, a continuously running 30 motor, a clutch between said motor and shaft, a pivoted member controlling the operation of said clutch, and a treadle operable to trip said member and then lose control thereof until after return of said treadle to initial position, and make the clutch effective to cause said shaft and elements carried thereby to make only one revolution, during which the "make" contact drops to close an electric circuit until the "break" contact drops to open said circuit.

3. A timing device comprising a shaft, a plurality of cam discs adjustably mounted on said shaft, a continuously running motor, a clutch between said motor and shaft, said clutch being normally in disengaged position, a solenoid, a pivoted clutch-release device operable by said solenoid, a device movable by an operator to close a circuit through said solenoid and allow said clutch to engage for turning said shaft and elements carried thereby through only 360°, and means terminating the operator's control of said 50 solenoid until a return of said device to initial position.

4. A timing device comprising a shaft, a plurality of cam discs adjustably mounted on said shaft, a "make" contact device resiliently urged into engagement with one of said discs, a "break" contact device resiliently urged into engagement with another of said discs, a continuously running motor, a clutch between said motor and shaft, a pivoted device normally holding said clutch from engagement, a solenoid operatively connected to said device, a treadle operable to close a circuit through said solenoid to withdraw said pivoted device and make the clutch effective, to cause said shaft and elements carried thereby to make only one revolution, during which the "make" contact drops to close an electric circuit until the "break" contact drops to open said circuit, and means breaking the control of said circuit by said

treadle after only one energization until return of said treadle to initial position.

5. A timing device comprising a shaft, a plurality of cam discs and a stop device adjustably mounted on said shaft, a pivoted latch normally engaged by said stop device, a continuously running motor, a clutch between said motor and shaft, and a release device operable to momentarily rotate the latch away from said stop device and allow the shaft and elements carried thereby to make only one revolution, and means then breaking the connection between said release and stop devices until after a return of the former to initial position.

6. A timing device comprising a shaft, a plurality of cam discs and a stop bar adjustably mounted on said shaft, a "make" contact device resiliently urged into engagement with one of said discs, a "break" contact device resiliently urged into engagement with another of said discs, a pivoted latch normally engaged by said stop bar, a continuously running motor, a clutch between said motor and shaft, a treadle operable to normally rotate the latch away and release said bar, to allow said shaft and elements carried thereby to make only one revolution, during which the "make" contact drops to close an electric circuit, until the "break" contact drops to open said circuit, and means then breaking the connection between said treadle and latch until after the former returns to initial position.

7. A timing device comprising a shaft, a plurality of cam discs with high and low dwells adjustable with respect to one another and mounted on said shaft, a "make" contact device resiliently urged into engagement with one of said discs, a "break" contact device resiliently urged into engagement with another of said discs, a continuously running motor, a clutch between said motor and shaft, a bevelled camming device normally preventing operation of said clutch, a solenoid operatively connected to said device, a treadle operable to close a circuit through said solenoid to withdraw said camming device and make the clutch effective, to cause said shaft and elements carried thereby to make only one revolution, during which the "make" contact drops from its high to its low dwell to close an electric circuit until the "break" contact drops from its high to its low dwell to open said circuit, and means breaking the control of said circuit by said treadle after only one energization until return of said treadle to initial position.

8. A timing device comprising a shaft, a plurality of cam disks with high and low dwells, and a stop bar adjustable with respect to one another and mounted on said shaft, a "make" contact device resiliently urged into engagement with one of said disks, a "break" contact device resiliently urged into engagement with another of said disks, a pivoted latch normally engaged by said stop bar, a continuously running motor, a friction clutch between said motor and shaft, a treadle operable to rotate the latch away and release said bar, to allow said shaft and elements carried thereby to make only one revolution, during which the "make" contact drops from its high to its lower dwell to close an electric circuit, until the "break" contact drops from its high to its low dwell to open said circuit, and means then breaking the connection between said treadle and latch until after the former returns to initial position.

9. A device for timing the application of electrical energy during welding operations comprising

10 ing a pivoted initiating lever, moving cam means and associated contact devices, means for readily adjusting the relationship between one of said contact devices and its cam means to alter the amount of energy delivered, operating means for said lever, and intermediate mechanism causing loss of control of said lever by said operating means after one actuation until return to initial position, whereby said timing means are moved, for performing only one timing cycle during each welding engagement.

15 10. In electric welding apparatus, a pair of electrodes, a timing device therefor, comprising a shaft, a plurality of cam disks with high and low dwells adjustable with respect to one another and mounted on said shaft, a "make" contact device resiliently urged into engagement with one of said disks, a "break" contact device resiliently urged into engagement with another of said disks, a continuously running motor, a clutch between said motor and shaft, a bevelled camming device normally preventing operation of said clutch, a solenoid operatively connected to said device, a treadle operable to bring the electrodes together and simultaneously close a circuit through said solenoid to withdraw said camming device and make the clutch effective, to cause said shaft and elements carried thereby to make only one revolution, during which the "make" contact drops from its high to its low dwell to close an electric circuit through the primary of a transformer, the secondary of which is in circuit with said electrodes, until the "break" contact drops from its high to its low dwell to open said circuit, and means breaking the control of said circuit by said treadle after only one energization until return of said treadle to initial position.

20 11. In electric welding apparatus, a pair of electrodes, a timing device comprising a shaft, a plurality of cam means with high and low dwells and a stop bar adjustable with respect to one another and mounted on said shaft, a "make" contact device resiliently urged into engagement with one of said means, a "break" contact device resiliently urged into engagement with another of said means, a latch normally engaged by said stop bar, a continuously running motor, a friction clutch between said motor and shaft, a treadle operable to cause engagement between said electrodes and what is to be welded and simultaneously pull the latch away to release said bar, allowing said shaft and elements carried thereby to make only one revolution, during which the "make" contact drops from its high to its low dwell to close an electric circuit through the primary of a transformer, the secondary of which is in circuit with said electrodes, until the "break" contact drops from its high to its low dwell to open said circuit, means for readily adjusting the relationship between one of said contact devices and its cam means to alter the amount of energy delivered, and means then breaking the connection between said treadle and latch until after the former returns to initial position.

25 12. A timing device comprising a shaft, cam means mounted on said shaft and provided with high and low dwells, "make" and "break" contact devices in series with a source of electrical energy and resiliently urged into engagement with said cam means, means for readily adjusting the relationship between one of said contact devices and its cam means to alter the amount of energy delivered, a treadle operable to close a circuit from said source and cause rotation of

said cam means and electrical current to pass through said "make" and "break" devices, only during a single period determined by the relative contact and cam setting, from the time the "make" contact drops from a high to a low dwell until the "break" contact drops from a high to a low dwell on said cam means, and means breaking the control of said circuit by said treadle after only one energization until return of said treadle to initial position.

13. A timing device comprising a shaft, cam means mounted thereon, means for causing said cam means to rotate continuously at substantially uniform speed, said cam means having high and low dwells, a "make" contact device resiliently urged into engagement with said cam means, a "break" contact device in series with said "make" device and resiliently urged into engagement with said cam means, a contact engageable by said "make" device when on a low dwell, a contact engageable with said "break" device when on a high dwell, a transformer with its primary connected to a source of electrical energy through said contacts, means for readily adjusting the relationship between one of said contact devices and its cam means to alter the amount of energy delivered, a control lever for initiating operation of the device, means to release said lever to start the timing operation, closing a circuit through said contacts as the cam means rotates, to pass current to said primary in series therewith, for a single period of time predetermined by the setting of the "break" device with respect to said cam means, and intermediate means causing loss of control of said lever release means after one actuation until return thereof to initial position.

14. In electric welding apparatus, a pair of electrodes, and means, including a pivoted lever, for timing the welding engagement thereof and insuring that only a predetermined quantity of energy is delivered during each operation, comprising moving cam means and associated contact devices for timing the application of electrical energy during welding operations, means for readily adjusting the relationship between one of said contact devices and its cam means to alter the amount of energy delivered, and means for simultaneously bringing said electrodes together and energizing said means, including operating means for said lever and intermediate mechanism causing loss of control of said lever by said operating means after one actuation until return to initial position, whereby said timing means are moved for performing only one timing cycle during each welding engagement.

15. In electric welding apparatus, a support, an electrode adjustably mounted on said support, a bracket, a shaft journaled therein, an arm fixed on said shaft, a movable electrode carried thereby for cooperating with said adjustably mounted electrode, a bell crank lever pivoted with respect to said shaft and having forwardly and rearwardly projecting arms, a forwardly projecting arm fixed on said shaft and having a lug projecting into the path of movement of the forwardly projecting arm of said bell crank lever, a rearwardly projecting arm fixed on said shaft, resilient means acting between said rearwardly projecting arm and the rearwardly projecting arm of said bell crank lever for holding said lug and forwardly projecting arm in engagement, means acting on the rearwardly projecting arm of said bell crank lever to hold the electrode-carrying arm in upper position with the movable

electrode separated from the adjustably-mounted electrode, switch means pivotally mounted on said bracket and having an operating extension lying in the path of movement of the forwardly projecting arm of said bell crank lever, a treadle, means operatively connecting said treadle and said forwardly projecting arm of said bell crank lever, whereby normal depression of said treadle first brings the movable electrode into engagement with said adjustable electrode, then momentarily closes said switch means, and finally opens said switch means, a timing device for the current supplied to said electrodes comprising a shaft, a plurality of cam disks with high and low dwells, adjustably-mounted with respect to one another, on said shaft, a "make" contact device resiliently urged into engagement with one of said disks, a "break" contact device resiliently urged into engagement with another of said disks, 10 a continuously running motor, a clutch between said motor and shaft, a bevelled camming device normally preventing operation of said clutch, and a solenoid operatively connected to said device and energizable by a circuit controlled by 15 said switch means so that when said switch means is closed by depression of the treadle, said solenoid withdraws said camming device and makes the clutch effective, whereby the shaft and elements carried thereby make only one revolution, 20 during which the "make" contact drops from its high to its low dwell to close an electric circuit to the primary of a transformer, the secondary of which is in circuit with said electrodes, until 25 the "break" contact drops from its high to its low dwell to open said circuit, after the application of a desired amount of energy to said electrodes.

16. In electric welding apparatus, a support, an electrode adjustably mounted on said support, a bracket, a shaft journaled therein, an arm fixed on said shaft, a movable electrode carried thereby for cooperating with said adjustably-mounted electrode, a bell crank lever pivoted with respect to said shaft and having forwardly and rearwardly projecting arms, a forwardly projecting arm fixed on said shaft and having a lug projecting into the path of movement of the forwardly projecting arm of said bell crank lever, a rearwardly projecting arm 45 fixed on said shaft, resilient means acting between said rearwardly projecting arm and the rearwardly projecting arm of said bell crank lever for holding said lug and forwardly projecting arm in engagement, means acting on the rearwardly projecting arm of said bell crank lever to hold the electrode-carrying arm in upper position with the movable electrode separated from the adjustably-mounted electrode, a treadle, means operatively connecting said treadle and said forwardly projecting arm of said bell crank lever, whereby normal depression of said treadle first brings the movable electrode into engagement with said adjustable electrode, a timing device for the current supplied to said electrodes comprising a shaft, a plurality of cam disks with high and low dwells, and a stop bar adjustably-mounted with respect to one another on said shaft, a "make" contact device resiliently urged into engagement with one of said disks, a "break" contact device resiliently urged into engagement with another of said disks, a latch normally engaged by said stop bar, a continuously running motor, a clutch between said motor and shaft, said treadle being also operable to pull the latch away and release said bar, after engagement be-

tween said electrodes, to allow the shaft and elements carried thereby to make only one revolution, during which the "make" contact drops from its high to its low dwell to close an electric circuit to the primary of a transformer, the secondary of which is in circuit with said electrodes, until the "break" contact drops from its high to its low dwell to open said circuit, after the application of a desired amount of energy to said electrodes.

17. In electric welding apparatus, a support, an electrode adjustably mounted on said support, a bracket, a shaft journalled therein, an arm fixed on said shaft, a movable electrode carried thereby for cooperating with said adjustably-mounted electrode, a bell crank lever pivoted with respect to said shaft and having forwardly and rearwardly projecting arms, a forwardly projecting arm fixed on said shaft and having a lug projecting into the path of movement of the forwardly projecting arm of said bell crank lever, a rearwardly projecting arm fixed on said shaft, resilient means acting between said rearwardly projecting arm and the rearwardly projecting arm of said bell crank lever for holding said lug and forwardly projecting arm in engagement, means acting on the rearwardly projecting arm of said bell crank lever to hold the electrode-carrying arm in upper position with the movable electrode separated from the adjustably-mounted electrode, a control device movable by an operator, means operatively connecting said device and the forwardly projecting arm of said bell crank lever, whereby normal depression of said device brings the movable electrode into engagement with the adjustable electrode, a timing device for the current supply to said electrodes comprising a shaft, a plurality of cam disks with high and low dwells adjustably mounted with respect to one another on said shaft, a "make" contact device resiliently urged into engagement with one of said disks, a "break" contact device

- resiliently urged into engagement with another of said disks, a continuously running motor, a normally ineffective clutch between said motor and shaft, said device being also operable, after engagement between said electrodes, to make said clutch effective and cause said shaft and the elements carried thereby to make only one revolution, during which the "make" contact drops from its high to its low dwell to close an electric circuit to the primary of a transformer, the secondary of which is in circuit with said electrodes, until the "break" contact drops from its high to its low dwell to open said circuit, after the application of a desired amount of energy to said electrodes.
18. In electric welding apparatus, a support, an electrode adjustably mounted on said support, a bracket, a shaft journalled therein, an arm fixed on said shaft, a movable electrode carried thereby for cooperating with said adjustably-mounted electrode, a bell crank lever pivoted with respect to said shaft and having forwardly and rearwardly projecting arms, a forwardly projecting arm fixed on said shaft and having a lug projecting into the path of movement of the forwardly projecting arm of said bell crank lever, a rearwardly projecting arm fixed on said shaft, resilient means acting between said rearwardly projecting arm and the rearwardly projecting arm of said bell crank lever for holding said lug and forwardly projecting arm in engagement, means acting on the rearwardly projecting arm of said bell crank lever to hold the electrode-carrying arm in upper position with the movable electrode separated from the adjustably-mounted electrode, a control device movable by an operator, and means operatively connecting said device and the forwardly projecting arm of said bell crank lever, whereby normal depression of said device brings the movable electrode into engagement with the adjustable electrode.
